UNITED STATES PATENT OFFICE.

EDWIN C. ROCKE, OF BLOOMINGTON, ILLINOIS.

SAFETY WRINGER MECHANISM.

Application filed December 19, 1921. Serial No. 523,253.

To all whom it may concern:

Be it known that EDWIN C. ROCKE, citizen of the United States of America, residing at Bloomington, in the county of McLean and State of Illinois, has invented certain new and useful Improvements in Safety Wringer Mechanism, of which the following is a specification.

My invention relates to safety wringers, and more particularly to a type of wringer which has additional wear compensating means for the wringer rolls.

The object of my invention is in the combination with a special safety wringer mechanism, of an adjustable yoke structure in connection with spring-pressed bearing blocks for compensating for the wear on the conventional wringer rolls.

Another object of my invention is in the provision of a spring-pressed safety closure member for housing the gears of the wringer.

Other objects of my invention will appear in the following specification, in connection with the annexed drawings, in which:—

Figure 1 is a front elevation of the safety wringer.

Figure 2 is a longitudinal sectional view thereof.

Figure 3 is a cross-sectional view on the line (AA) of Figure 2.

Figure 4 is a cross-sectional view on the line (BB) of Figure 2.

Figure 5 is a cross-sectional view on the line (CC) of Figure 2.

Figure 6 is an enlarged detail of my special yoke member.

Referring to the drawings, in Figure 1 is shown generally a safety wringer formed in two main sections, namely 10 and 11. The section 10 we will call the stationary portion, or base, while the portion 11 will be hereafter referred to as the movable section. This base has a semi-circular bottom 13, with upwardly projecting portions 14 and 15 integrally cast therewith, and forming the sides of the entire wringer. The downwardly projecting lugs 16 and 17 and the adjustable screw mechanism 18, form the attachment means for the wringer, with the

conventional washing machine, (not shown). A guide member is shown at 19, whereby articles passing between the wringer rolls will be carried therefrom. The upwardly projecting portions 20 and 21, cast integrally with the base 10, form guide-ways for bearing blocks 22 and 23, for the power shaft 24, which carries thereon the power roll 25. The outer end 26, of the power shaft is capable of engagement with the power shaft of the washing machine (not shown). Gears 27 and 28 have positive connection with the power shaft and engage similar gears 29 and 30 mounted on the end of the shaft 31, which carries the upper or movable wringer roll 32. The upper or movable portion 11 of the wringer is formed in such manner that it incases substantially all of the wringer mechanism, besides the wringer rolls, that is not covered by the base portion. This upper casing is pivotally mounted at 33 and 34 to the side portions 14 and 15 respectively, and is free to pivot in either direction on these lugs. A lever 35 has a loose connection as at 35^a. The lever 35 at its inner end 36, is fashioned to engage apertures 37 and 38 in the side 14, and upper casing 11 respectively. The spring 39 seats within the lug 33, which is one of the pivots for the upper casing, said spring abutting at its other end, the inner side of the lever 35. The above lever mechanism provides means for engaging the upper casing and holding it in operative position with relation to the lower casing. An adjustable screw 40 projects through an aperture in the upper casing, and has its inner or threaded end 41 screwed into a block 42, which forms the intermediate portion of a spring bar 43. This spring bar rests at either end upon wooden plugs 44, and 45, which form the bearings for the shaft 31, of the upper wringer roll. The adjustable screw 40, above described, provides means for applying a pressure to the wooden bearing blocks. The two coil springs 46 and 47 engage with seating lugs 48 and 49 respectively, cast integrally with the upper casing, said springs having their lower ends abutting the upper side of the spring bar 43. Integrally cast with the upper casing and in-

teriorly thereof are guide-ways 50 and 51 which carry the yoke members 52 shown in detail in Figure 6 of the drawings. These yoke members, as shown in Figure 2 carry 5 the wooden bearing blocks 44 and 45 therein, and inasmuch as the upper ends of the yoke members have adjustable connection as at 53 with the nuts 54, they form an adjustable means for supporting the upper wringer 10 roll shaft 31. In the drawings I have shown this adjustable connection by means of screws passing through the upper end of the yoke member, and their threaded portions engaging nut members. Also I have 15 shown small coil springs 55 surrounding the screws. Within the contemplation of my invention, and perhaps more practicable of application, would be the casting of the yoke and screw member, as a unit, and for 20 this reason I wish to include the screws as portions of the yoke, when I refer to said yoke members, hereafter. Brackets 56 have positive connection with the power shaft 24 and enclose the outer end of the power roll. 25 These brackets are bifurcated at their upper ends, with the result that they partially enclose the outer ends of the upper or movable wringer roll. As is shown in Figure 1 of the drawings, the peculiar form of the upper 30 casing and the base portion leaves an opening at the side thereof. This opening is necessary for the pivotal movement of the upper casing, and the relationship of the gears of both sections. Should this space 35 be left open, accidents might occur due to the exposure of the revolving gears. I have provided a special means for enclosing this opening, which is at either side.

The closure plate 57 having the arms 58 40 and 59, is pivotally mounted on the small shaft 60 which engages hubs 61 in the base portion 10. A coil spring 62 surrounding this shaft has one of its ends abutting the base portion and the other, the closure plate, 45 and in such manner, that said closure plate is held in the aperture formed by the upper and lower portions. The peculiar projection 63 on the closure plate, engages the side 14 of the wringer, and determines the 50 exact inner position thereof.

The operation of the safety wringer is, as follows:

In any emergency, or rather, should it be desired that the wringer rolls be thrust 55 apart, the lever 35 is struck at its upper end, thereby drawing the inner end 36 out of engagement with the aperture 38 in the upper or movable casing. The pressure between the wringer rolls causes the upper casing to 60 be thrown outwardly at either side, thereby disengaging the two rolls. Inasmuch as there is pressure applied at all times by the spring bar 43, on the bearing blocks 44, and 65 45, when the two rolls are again thrust together with some effort, the spring pressed

lever, or rather its inner end 36 thereof, will again engage the aperture in the upper casing and again locate positively said casing with relation to the base portion.

Prior to the forming of my special yoke 70 means, compensating for wear on the wringer rolls, the wooden bearing blocks 44 and 45 had a fixed position, or rather a fixed lower position with relation to the shaft 31, the usual structure being to have 75 a screw passing entirely through the upper casing and acting as a seat for the shaft 31 at either end. With the above structure, any wear upon the wringer rolls above a slight amount, could only be taken care of 80 by the insertion of new rolls, but with my special yoke mechanism, by loosening the nuts 54, it is possible to lower either end of the shaft 31, and at the same time, the upper wringer roll, thereby compensating for any 85 wear at any point on either roll.

It may be seen from the above that, no matter how worn the rolls may become, or at whatever point thereon, my special yoke mechanism will compensate therefor, and instead of having to replace the wringer rolls 90 after they have been slightly worn, I am able to use them until they are entirely worn out.

What I claim is:—

1. In a wringer mechanism, in combination, a base portion, a lower roll therein, and upwardly projecting end members, an upper casing pivotally mounted on said end members, said upper casing having an adjustable upper wringer roll, bearing blocks for the said upper wringer roll, spring plates abutting the upper sides of the bearings, adjustable means for tensioning said spring plates, and means for positioning either end 100 of the upper wringer roll with relation to said lower roll, including yoke members, and adjustable means between said yoke members and the upper casing.

2. In a safety wringer mechanism, in combination, a base portion, including a lower roll therein, and upwardly projecting side portions, an upper casing pivotally attached to said side portions, a tension lever providing engagement means between the upper 110 casing and base portion, an upper wringer roll, adjustable spring means for applying pressure upon both ends of the upper wringer roll simultaneously, and means including yoke members for adjustably locating either end of the upper wringer roll 120 with relation to the lower roll.

3. In a safety wringer mechanism, in combination, a base portion including therein a lower roll having gear connections at one 125 end, said base portion having an opening therein adjacent said gears, an upper casing pivotally mounted with relation to said lower casing including therein a spring-pressed upper wringer roll, gears on one 130

end of the upper wringer roll meshing with the gears on the lower roll, said upper casing having an opening adjacent the gear members, means on the base portion capable of engagement or disengagement with the upper casing to provide means for holding said portions in operative position, and a

spring-tensioned member related to the upper and lower casings in a manner to provide means for closing the opening between 10 said members.

In testimony whereof I affix my signature.

EDWIN C. ROCKE.
